(57) **CLAIM**

The ornamental design for a clip for a medical pole assembly, as shown and described.

DESCRIPTION

FIG. 1 is a front, top, and left side perspective view of a clip for a medical pole assembly embodying our new design;

FIG. 2 is a left-side view thereof;

FIG. 3 is a right-side view thereof;

FIG. 4 is a front view thereof;

FIG. 5 is a rear view thereof;

FIG. 6 is a top view thereof; and,

FIG. 7 is a bottom view thereof.

Broken lines are used to illustrate portions of the clip for a medical pole assembly that form no part of the claimed design.

1 Claim, 7 Drawing Sheets
